UNITED STATES PATENT OFFICE.

CHARLES L. DUNHAM, OF PENNSBORO, WEST VIRGINIA.

UNDERREAMER.

1,348,853.

Specification of Letters Patent. Patented Aug. 10, 1920.

Application filed May 15, 1920. Serial No. 381,721.

To all whom it may concern:

Be it known that I, CHARLES L. DUNHAM, a citizen of the United States, residing at Pennsboro, in the county of Ritchie and State of West Virginia, have invented certain new and useful Improvements in Underreamers, of which the following is a specification.

This invention relates to underreamers and the object thereof is to provide a device of the character stated, in a manner as hereinafter set forth, for enlarging the bore of a well at any desired point thereof, but it is to be understood that the device may be used for any purpose wherein it is found applicable.

Further objects of the invention are to provide a device of the type specified which is simple in its construction and arrangement, strong, durable and efficient in its use, formed of few parts, readily assembled, and comparatively inexpensive to manufacture.

To the accomplishment of these and such other objects as may hereinafter appear, the invention consists of the novel construction, combination and arrangement of parts herein specifically described and illustrated in the accompanying drawing wherein is shown an embodiment of the invention, but it is to be understood that changes, variations and modifications may be resorted to which come within the scope of the claims hereunto appended.

In the drawing forming a portion of this specification and wherein like numerals of reference designate corresponding parts throughout the several views:

Figure 1 is an elevation of an underreamer in accordance with this invention.

Fig. 2 is an elevation of an underreamer, partly in section, extended into a casing also in section.

Fig. 3 is an elevation of the underreamer with one of the drilling bits removed.

Fig. 4 is an inverted plan view of the underreamer extended into a casing.

Referring in detail to the drawing 1 denotes the body portion of the underreamer having a bifurcated lower end formed by the transverse slot 2. A pair of opposed cutters 3, each provided with a shank 4, at its upper end, extending into the slot 2, are pivotally connected by means of the pins 5, which extend through the body portion 1 and through respective shanks of the cutters 3 in the slot 2.

A pair of opposed and longitudinally extending dovetailed slideways 6 are formed on the periphery of the body portion 1 at the lower end thereof. The slideways 6 taper inwardly toward each other at their lower ends, that is, each of the said slideways is of greater depth at its lower end than at its upper end. An actuating member 7, having a dovetailed portion 8, is slidably mounted for vertical movement in each of the slideways 6.

A transversely extending rod 9 is loosely carried by the lower ends of the actuating members 7 to which a pair of spreaders 10 are pivotally connected. Another transversely extending rod 11 is loosely carried by the lower ends of the actuating members 7 which is positioned above the rod 9 and to which the lower end of the spring 12 is connected. The upper end of the spring 12 is attached to the rod 13 extending transversely across the slot 2. The action of the spring 12 is such as to normally hold the actuating members 7 in the extreme upward position in the slideways 6.

Each of the spreaders 10 has an enlarged rounded outer end 14 which engages in the respective pocket or slot 15 formed therefor in the facing sides of the opposed cutters 3, as clearly shown in Fig. 2 of the drawing.

The actuating members 7 are each provided with a projecting portion 16 which extends outwardly from its respective slideway 6 and has an inclined upper end 17.

The action of the spring 12 will normally hold the cutters 3 extended by extending the spreaders 10, but when the underreamer is moved upwardly through the casing 18, the latter will force the actuating members 7 downwardly by its engagement with the projecting portions 16 thereof. Owing to the greater depth of the slideways 6 at their lower ends, the downward movement of the actuating members 7 will permit its passage through the casing 18 and cause the contraction of the cutters 3 also permitting their passage through the casing.

The construction of the cutters 3 is such as to provide a clearance 19 between their lower ends and the inner wall of the casing 18 when the said cutters 3 are contracted to facilitate the downward passage of the reamer through the casing 18.

When the cutters 3 are extended the shoulders 20 thereof abut against the lower end 21 of the body portion 1 thereby carry-

ing the strain of the reaming operation which otherwise would be borne by the pins 5 which connect the cutters 3 with the body portion.

5 What I claim is:

1. A reamer comprising a body portion having its lower end bifurcated and further provided with peripheral slideways, cutters having shanks extended into the furcation 10 of and pivotally connected to the body portion, spreaders engaging the cutters, and spring controlled actuating means for the spreaders shiftable in the slideways.

2. A reamer comprising a body portion 15 having its lower end bifurcated and further provided with peripheral slideways, cutters having shanks extended into the furcation of and pivotally connected to the body portion, spreaders engaging the cutters, and 20 spring controlled actuating means for the spreaders shiftable in the slideways, said spreaders pivotally connected with said actuating means.

3. A reamer comprising a body portion 25 having its lower end bifurcated and further provided with peripheral slideways, cutters having shanks extended into the furcation of and pivotally connected to the body por-

tion, spreaders engaging the cutters, and spring controlled actuating means for the 30 spreaders shiftable in the slideways, said actuating means including actuating members having said spreaders pivotally connected therewith.

4. A reamer comprising a body portion 35 having its lower end bifurcated and further provided with peripheral slideways, cutters having shanks extended into the furcation of and pivotally connected to the body portion, spreaders engaging the cutters, and 40 spring controlled actuating means for the spreaders shiftable in the slideways, said cutters having slots for the reception of the spreaders and said spreaders having enlarged outer ends. 45

5. A reamer comprising a body portion, a pair of cutters pivotally connected therewith, spreaders engaging the cutters to maintain them extended, and a spring controlled actuating means for the spreaders, 50 said actuating means slidably mounted on the periphery of the body portion and having said spreaders pivotally connected therewith.

In testimony whereof I affix my signature. 55
CHARLES L. DUNHAM.
